United States Patent Office

Des. 186,819
Patented Dec. 8, 1959

186,819

VEGETABLE BIN

Robert L. Schaefer, River Grove, Ill., assignor to Republic Molding Corporation, Chicago, Ill., a corporation of Illinois

Application January 19, 1959, Serial No. 54,227

Term of patent 14 years

(Cl. D44—1)

Fig. 2 is a view looking downwardly into the bin shown in Fig. 1;

Fig. 3 is a bottom view of the bin shown in Fig. 1;

Fig. 4 is an elevational view looking at the front face; and

Fig. 5 is an elevational view of one side of the bin.

I claim:

The ornamental design for a vegetable bin, substantially as shown.
